UNITED STATES PATENT OFFICE.

ALBIN C. ROTHOFF, OF BROOKLYN, NEW YORK, ASSIGNOR TO WETTER NUMBERING MACHINE COMPANY, OF BROOKLYN, NEW YORK, A CORPORATION OF NEW YORK.

NUMBERING MACHINE.

Application filed March 2, 1928. Serial No. 258,497.

This invention relates to type-high numbering machines, such as are commonly locked in the form with type and comprise a series of number wheels which are actuated in the operation of a press by a plunger and intermediate mechanism. Many of the printing presses in which such numbering machines are used are operated at such high speed that the roller which coacts with the 10 plunger of the numbering machine acts on the plunger with a hammer-like blow. The tendency of this action is to cause the number wheels to overrun and it is the object of the present invention to provide improved means whereby this tendency shall be overcome and the number wheels shall be stopped in printing position.

The invention will be more fully explained hereinafter with reference to the accompanying drawing in which it is illustrated and in which:

Figure 1 is a top view of a numbering machine which embodies the invention, with the number wheels in intermediate positions.

Figure 2 is a view of the same in elevation as seen from the right hand in Figure 1, with the end plate broken away to show parts behind it.

Figure 3 is a view of the same in side elevation, with the side plate broken away, some parts in section and the number wheels in intermediate positions.

Figure 4 is a view in section on the plane indicated by the broken line 4—4 of Figure 3, but with the parts in printing position.

Figure 5 is a view in elevation as seen from the opposite side from that represented in Figure 3, the spring plate which coacts with the detent pawls being broken away and the number wheels being shown in intermediate positions.

Figure 6 is a view in section on the plane indicated by the broken line 6—6 of Figure 3, but with the parts in printing position.

Figure 7 is a view in section on the plane indicated by the broken line 7—7 of Figure 8.

Figure 8 is a view in section on the horizontal plane indicated by the broken line 8—8 of Figure 3, the number wheels being omitted and some parts broken away.

Except as to the means for checking the movement of the number wheels, the construction of the numbering machine may be of any usual or preferred form. In order

that the application of the invention may be understood that form of construction of the numbering machine which has been chosen for illustration of an embodiment of the invention, will be described briefly. 60 This form of the machine comprises a suitable casing *a* in which is fixed a shaft *b*. Typographic number wheels *c* are mounted to rotate on the shaft *b* and are actuated in the usual manner by the swinging pawl frame *d* which carries a series of spring-pressed pawls *d*¹ adapted for engagement with suitable ratchet wheels *c*¹ formed with or secured to the number wheels *c* respectively. One of the cheek pieces *d*² of the 65 swinging pawl frame is engaged by a pin *e* which projects through a slot in the partition plate *a*¹ of the casing from a plate lever *e*¹ pivoted at *e*² on the vertically movable spring-pressed plunger *f* and engaging a pin *e*³ on the casing *a*. The plunger *f*, bearing on its upper end a type character or other device *f*¹ adapted for contact with the roller or platen of the printing press, is held normally in its elevated position, with 70 its upper end above the plane of print, by the springs *f*² on which it is seated. It will be understood that through the depression of the plunger by the action of the press and its raising by the springs *f*² the pawl frame *d*² receives an oscillatory movement 75 by which the desired forward movement of the number wheels is effected and the pawl frame is placed in position for another operation. Arranged for coaction with each 80 ratchet wheel *c*¹ is a hold-back pawl or detent *g* which is normally held yieldingly in engagement with the ratchet wheel by a spring *h*, serving normally to prevent backward rotation of the ratchet wheel and corresponding number wheel. 85

In accordance with the present invention a means is provided whereby all of the detents or hold-back pawls *g* are pressed positively against the respective ratchet wheels 90 *c*¹ as the swinging pawl frame *d* completes its effective movement, whereby the continued forward movement of the number wheels, under the influence of their own momentum, is prevented and the number wheels 95 are stopped in the correct printing position. Pivots mounted in proximity to the detents *g* and, it may be, on the rod *g*¹ on which the detents are pivotally supported, 100 is a frame composed of two plates or cheek 105 *g*² which are pivotally connected to the rod *g*¹ and the frame is pivoted at 110

pieces i and a rod i^1 , the rod i^1 being positioned back of the upper ends of the detents g , with sufficient clearance normally to permit the free action of the detents as the ratchet wheels are actuated. One of the plates or cheek pieces i is formed with a tooth i^2 for engagement with the corresponding tooth d^3 of the corresponding cheek piece d^2 of the swinging pawl frame. The coacting teeth i^2 and d^3 are so formed and related that as the swinging pawl frame nearly approaches the limit of its effective movements, the frame i, i^1 is swung upon its pivot to move the rod i^1 against the detents g and force them against the respective ratchet wheels thereby locking the ratchet wheels and the several number wheels against further movement. This action takes place as will be understood, just as the number wheels have reached the printing position. As the pawl frame swings back to its initial position the frame i, i^1 swings back away from the detents g which are then held yieldingly by the springs h . It will be observed that each detent g is formed with the heel h^2 to limit its rearward movement.

It will be understood that various changes in details of construction and arrangement can be made to suit different forms of num-

bering machines and that, except as pointed out in the claims, the invention is not restricted to the particular construction shown and described herein.

I claim as my invention:

1. In a numbering machine which has a number wheel, a ratchet wheel associated with the number wheel, a swinging pawl frame and a detent for coaction with the ratchet wheel, means actuated by the swinging pawl frame to press the detent positively against the ratchet wheel in the last of the effective movement of the pawl frame to prevent continued movement of the ratchet wheel and number wheel. 35
2. In a numbering machine which has number wheels, ratchet wheels associated with the number wheels, a swinging pawl frame and detents for coaction with the ratchet wheels, a frame pivoted in operative relation with the detents and having a rod to cooperate with the detents, the pawl frame and the last named frame being operatively engaged to effect movement of rod against the detents in the last of the 40 effective movement of the pawl frame. 45

This specification signed this 29th day of February A. D., 1928.

ALBIN C. ROTHOFF.
